CLAIM

The ornamental design for a vibrating massage roller, as shown and described.

DESCRIPTION

FIG. 1 is a perspective view of a vibrating massage roller showing my new design;

FIG. 2 is a right side view of the vibrating massage roller; FIG. 3 is a left side view of the vibrating massage roller; and, FIG. 4 is a top view of the vibrating massage roller, the bottom, front, and back views being a mirror image thereof. The broken lines in the drawings are for the purpose of illustrating portions of the vibrating massage roller, which form no part of the claimed design.
